UNITED STATES PATENT OFFICE

ORVILLE C. JOHNSON, OF AURORA, ILLINOIS, ASSIGNOR TO JOHNSON IDEAL HALTER CO., OF AURORA, ILLINOIS

HALTER

Application filed April 1, 1929. Serial No. 351,508.

This invention relates to a rope or cord halter and constitutes an improvement upon the halter disclosed in my Patent No. 1,138,115. In the halter disclosed in said patent, the chin piece constitutes a portion of the cord that goes to make up the halter proper. As the chin piece is frequently dipped into the water when the horse is drinking or is dipped into the feed box, it soon deteriorates and decays, with the result that the life of the halter is greatly reduced.

It is an object of this invention to overcome the objections above noted and to this end the halter is so designed that the main portion of the cord does not form a chin piece; a separate chin piece of different material that will not readily deteriorate being used for such chin piece. In the present case, the formation of the cord is such that the nose piece constitutes an integral part of the halter proper with the chin piece connecting the ends of the same as will more fully herein-after appear.

This invention comprises the novel structure and combination of parts hereinafter described and more particularly pointed out and defined in the appended claim.

In the accompanying drawings which illustrate a preferred embodiment of this invention and in which similar reference numerals refer to similar features in the different views:

Figure 1 is a perspective view of an animal's head wearing a halter involving this invention.

Figure 2 is an enlarged fragmentary elevational view of a portion of the halter showing the nose piece and chin piece in their connected relation.

Figure 3 is a side elevational view of the throat connections to the chin piece.

Figure 4 is a front elevational view of the throat connection to the chin piece.

Figure 5 is a fragmentary side elevational view of the connections between the nose and cheek piece with the chin piece.

Figure 6 is a front elevational view of the structure shown in Figure 5.

Figure 7 is a plan view of a connecting anchor.

In referring to the drawings, it will be noted that the halter with the exception of the chin piece, is made from a single piece of cord or rope and appropriate clamps. The free end of the cord is represented by the reference numeral 1 in Figure 1 and in tracing this cord, it will be noted that it passes through a buckle 2 thence over the head of the horse and passes around a prong of an anchor member 3. The cord then returns over the horse's head through the double clamp 13 and passes down the side of the head forming a cheek piece as indicated at 4. The loop of the rope 4 passes through the eyelet 5 of a clamp and eyelet member 6 and passes around the shank of the eyelet member and back through the eyelet 5 and over the nose of the horse forming the nose piece 6'. The nose piece 6' then passes through a second clamp 5 of a combined clamp and eyelet member similar to the clamp and eyelet member 5-6 before described and around the shank of said eyelet member and then extends upwardly to form the cheek piece, and a loop extends through an eyelet 3' on the anchor member 3 and around the shank thereof. The return branch of the rope after extending through the eyelet 3' is designated by the reference numeral 8. The branch 8 passes down through a buckle 9 and through an eyelet 10 of a ring member 11; the eyelet being at right angles to the plane of the ring portion. The branch 8 passes around the shank of the ring member 11 and then returns through the eyelet 10 forming a branch 12 which also passes through the buckle 9 and extends through the lower end of the buckle 2 where it is clamped to the branch 4 by means of the double clamp member 13. It will be noted that the buckle 2 is secured to the branch 12 of the rope between the ends of the double clamp 13.

The chin piece of the halter is a short chain 14 that is therebetween and connected at its ends to the ring members 6 and passes through the ring 11. This ring 11, of course, affords attachment for any suitable halter lead.

It will be obvious that the rope halter in-

volving this invention can be easily and quickly assembled and adjusted. The adjustment of the head stall is quickly effected by shifting the free end of the rope 1 through 5 the buckle 2 thereby increasing or decreasing the head stall as desired. The throat latch can be quickly adjusted by shifting the buckle 9. On account of the independent character of the chin piece 14, any injury 10 thereto will not affect the halter proper. In the event that the chin piece should become broken or worn out, it may be readily replaced by another. This characteristic obviously avoids throwing the halter away 15 should the chin piece break.

I am aware that many changes may be made, and numerous details of construction may be varied through a wide range without departing from the principles of this 20 invention, and I therefore do not purpose limiting the patent granted hereon, otherwise than necessitated by the prior art.

I claim as my invention:

25 A halter comprising a single length of flexible material having one end secured by a clamp member, thence passing through an adjusting buckle to a ring member where it doubles back to form a throat latch and again passes through said adjusting buckle to an anchor member having a prong, through said anchor member to a clamp of an eyelet member for forming a cheek piece, thence to the clamp of a second eyelet member for forming a nose piece, thence to said 30 first clamp member for forming a companion cheek piece, through said clamp member to said anchor member and return for forming a crown piece and loop for engaging the prong of said anchor member, the free 35 end thereof passing through an adjusting buckle associated with said clamp member, and a flexible metallic member connecting said eyelet members and passing through said ring member to form a chin piece.

40 45 In testimony whereof I have hereunto subscribed my name at San Diego, San Diego County, California.

ORVILLE C. JOHNSON.
